Primary Examiner — John Windmuller*Assistant Examiner* — John R Yeh(74) *Attorney, Agent, or Firm* — Nixon & Vanderhye PC(57) **CLAIM**

The ornamental design for an antenna, as shown and described.

DESCRIPTION

FIG. 1 is a first perspective view showing our design for an antenna;

FIG. 2 is a front elevation view thereof;

FIG. 3 is a rear elevation view thereof;

FIG. 4 is a top plan view thereof, enlarged to show additional detail;

FIG. 5 is a bottom plan view thereof, enlarged to show additional detail;

FIG. 6 is a right side view thereof;

FIG. 7 is a left side view thereof; and,

FIG. 8 is a second perspective view thereof.

The broken lines in the figures represent features of the antenna which form no part of the claimed design.

1 Claim, 5 Drawing Sheets(56)
